UNITED STATES PATENT OFFICE.

ALVIN D. KEENE, OF PITTSBURGH, PENNSYLVANIA, ASSIGNOR TO WESTINGHOUSE ELECTRIC & MANUFACTURING COMPANY, A CORPORATION OF PENNSYLVANIA.

ELECTRIC HEATING UNIT.

Application filed December 13, 1923. Serial No. 680,393.

To all whom it may concern:

Be it known that I, ALVIN D. KEENE, a citizen of the United States, and a resident of Pittsburgh, in the county of Allegheny and State of Pennsylvania, have invented a new and useful Improvement in Electric Heating Units, of which the following is a specification.

My invention relates to electric heating devices and particularly to heating units for electric resistance furnaces.

The object of my invention is to provide a relatively simple and compact structure for a quickly removable and self-contained heating unit of relatively high capacity, that shall have both ends of the resistor element located at one end of the unit.

In practicing my invention, I provide a relatively heavy resistor wire that is wound in the form of a flat helix of double pitch, the adjacent turns of which are spaced from each other. Refractory members, of electric-insulating material, each having a plurality of spaced pockets in one face thereof, operatively engage the end portions only of each turn.

A metal frame having side portions of overhanging channel section interfit with the refractory members to hold them in their proper operative positions, metal end pieces being provided to complete the metal frame and provide a substantially unitary structure. The two ends of the resistor member extend through suitable bushings in one of the end pieces of the metal frame.

In the drawings,

Figure 1 is a view, in vertical longitudinal section, through an electric furnace comprising the device embodying my invention. Fig. 2 is a view, partially in side elevation and partially in longitudinal vertical section, of an electric heating unit embodying my invention, and

Fig. 3 is a view in vertical lateral section therethrough taken on the line III—III of Fig. 2.

An electric resistance furnace 11 comprises a plurality of outer side and end walls 12, a bottom wall 13 and a top wall 14, each made of suitable refractory heat-insulating bricks or blocks. An inner lining 15 is provided for each of the outside walls and may

comprise a plurality of bricks or blocks of a suitable high-temperature resisting refractory material usually employed in the art. 55

The walls are so spaced apart as to provide a furnace chamber 16, of any suitable or desired contour and dimensions. I have shown a particular furnace structure for illustrative purposes only in order to show more particularly the application of and the location in, such a furnace structure of a heating unit embodying my invention and to be hereinafter described in detail. 60

A heating unit 17 comprises a relatively heavy resistor member 18 in the form of a wire or rod that is preformed to the shape of a flat helix, as is illustrated more particularly in Fig. 3 of the drawing. The helix is so wound as to have a double pitch, a construction that may be obtained by bending the necessary length of resistor member 18 at substantially the middle point of its length and then winding the same with a uniform spacing between the adjacent turns 75 of the helix. The distance between adjacent turns of the helix is in accordance with the dimensions of the wire and the dimensions of the helix, as well as in accordance with the object of having as much as possible of the heat radiating surface of the resistor member so located that the heat generated thereby or therein will have a free and unobstructed path from the surface of the resistor member to material, to be heated 80 thereby and located adjacent thereto. 85

A plurality of refractory supporting members 19 of a suitable electric-insulating and high temperature resisting material, are provided, and each has a plurality of spaced pockets 21 in the inner face thereof into which the rounded end portions of each turn of the resistor member 18 may fit. The distance between the adjacent turns of the resistor member 18 should be at 95 least sufficiently large to make the walls between the adjacent pockets 21 sufficiently heavy to resist such strains as may be placed thereon during the assembly and disassembly of the heating units and during the operation thereof. 100

A metal frame for the refractory members 19, a plurality of which may be located in end-to-end relation at each side of

the flat helix comprises a pair of metal side members 22, of substantially overhung channel form in lateral section. The overhanging flanges of the side members 22 co-
5 operate with the refractory members 19 to interfit therewith and to prevent any movement of the refractory members laterally of their length. A shoulder portion 23 is provided at each side of the members 19 to
10 permit of this interfitting relation.

End members 24, of a suitable length, are provided and are secured to the side members 22 by a plurality of bolts 25. As the temperature of the heating unit is relatively high, it is desirable that all of the metal portions of the frame be made of a substantially non-oxidizable material, and I prefer to employ the material called nichrome for this purpose.

20 One of the end members 24 is provided with a plurality of spaced openings 26 therethrough in which are located bushings 27 of refractory electric-insulating material having an opening therethrough, through
25 which the ends of the resistor member 18 may extend, as shown more particularly in Fig. 2 of the drawing.

The bushings 27 are provided with a radial flange at one end and a spring clamping ring 28 located in a peripheral groove adjacent to the other end to hold the bushings in their proper operative position within the openings 26 during the operation of the heating unit.

30 In assembling the heating unit, the two side members 22 and one end member 24 may be bolted together and laid in their proper operative positions on a suitable supporting surface after which the members 19 may be moved into their positions longitudinally of the side members 22 from the open end of the unit. The resistor member 18 may be placed in its proper operative positions relatively to the refractory members 19, before the latter are moved into their proper operative positions, and it is only necessary then to place in position the end member 24 having the bushings 27 therein and then bolt the end members as
45 hereinbefore described.

50 Another method of assembly that may be employed is to place the refractory members in their proper operative positions against the ends of the resistor member and then place the side and end metal members in their proper operative positions, the side members 22 being moved longitudinally of their length to receive the refractory members, after which they may be bolted together, as hereinbefore described and as illustrated in the drawing.

60 In Fig. 1 of the drawing, I have illustrated several methods according to which I may assemble a plurality of heating units 17 of the hereinbefore described type, closely

adjacent to the side or the end walls of a furnace structure. For instance, I may mount a plurality of heating elements 17 in superposed relation, as is illustrated more particularly in the right hand part of Fig. 70 1 of the drawing, it being understood, of course, that the width or height of each heating unit is such that substantially all of the surface of the side wall may be covered with heating units.

75 Instead of bolting the side and end members of each heating unit, I may employ somewhat longer bolts, that secure together not only the end members to the side members of a particular heating unit, but, also, 80 those members of adjacent heating units, thereby providing a substantially unitary structure comprising a plurality of individual heating units bolted together.

85 In the left-hand end portion of Fig. 1, I have illustrated another method of mounting the heating unit embodying my invention in a furnace structure, in which case, the individual heating units rest upon an end surface thereof, which is, of course, the 90 one opposite to that end having the ends of the resistor member projecting therefrom.

95 As the resistor rod or wire is relatively heavy, it is possible to place the individual 100 heating units in either of these positions, as well as in a substantially horizontal or flat position above or below a heating chamber, without appreciable deformation of the straight portions of the resistor member.

105 Any suitable or desired means may be employed to hold the individual or assembled plurality of heating units in their proper operative positions within the furnace structure and I have indicated two 110 methods in Fig. 1 of the drawing. I may provide grooves 29 in the inner surface of the lining 15, substantially as indicated in the right hand portion of Fig. 1 of the drawing, into which the individual or assembled heating units may be placed, either by a movement longitudinally of the groove 29 or if the depth of the upper groove 29 is made greater than that of the other or lower groove 29, the assembled heating units 115 may be placed in their proper operative positions by a lateral or tilting movement thereof, the upper end of the heating unit being placed in the deeper groove 29 and then moved upwardly until the lower end clears 120 either the refractory lining adjacent to the groove 29 or until it clears the upper edge of a heating unit 17 already installed.

125 Another means of holding the individual or assembled heating units, may comprise metal rods 31 built into the furnace structure and key members 32, of substantially L-shape, extending laterally through an opening in the rod 31 adjacent to the outer end thereof and engaging a part of the 130

metal frame of the heating units. This construction is illustrated more particularly in the left-hand portions of Fig. 1 of the drawings.

5 Any suitable or desired means for connecting the ends of the respective resistor members may be employed, but I prefer to employ my oxide connector that is more particularly disclosed and claimed in my co-pending application, Serial No. 649,781, filed July 6, 1923, and assigned to the Westinghouse Electric & Mfg. Co.

10 The end portions of the resistor member that are connected to the ends of suitable supply circuit conductors (not shown) are preferably bent at right angles to the plane of the individual heating unit in order that the heating units may be installed by a movement substantially at right angles to the plane thereof and these end portions may extend through suitable bushings 33 provided in the furnace structure.

15 The bushings 33 may be of any suitable or desired construction and, as they form no part of my invention, they are not further described nor illustrated.

20 The device embodying my invention thus provides a heating unit that may be placed and supported in a plurality of operative positions, such as on edge at either side or at one end thereof, or flat upon a suitable skeleton supporting frame, and in which frame both ends of the resistor wire are located at one end of the heating unit, whereby easy and quick connection of operatively assembled heating units may be effected.

25 Various modifications and changes may be made without departing from the spirit and scope of the invention, I desire, therefore, that only such limitations shall be

placed therein, as are imposed by the prior art.

I claim as my invention:

1. In an electric heating unit, the combination with a metal frame, and a plurality of refractory members supported thereby and having a plurality of spaced pockets in one surface thereof, of a resistor member wound in a double pitch flat helix extending between spaced refractory members and having the rounded end portions located in said pockets. 45

2. In an electric heating unit, the combination with a metal frame having two side members of substantially overhanging channel section and a plurality of refractory members located in and supported by said side members and each having a plurality of spaced pockets in the outer face thereof, of a resistor member wound in the form of a double pitch flat helix extending between spaced refractory members and having the rounded end portions located in said pockets. 55

3. In an electric heating unit, the combination with a metal frame, and a plurality of refractory members supported thereby and having a plurality of spaced pockets in one surface thereof, of a resistor member wound in a double pitch flat helix extending between spaced refractory members and having the rounded end portions located in said pockets, and a plurality of spaced refractory thimbles supported by said frame at one end thereof for receiving and supporting the ends of said resistor member. 70

75 In testimony whereof, I have hereunto subscribed my name this 28th day of November, 1923.

ALVIN D. KEENE.
